UNITED STATES PATENT OFFICE.

ANDREW BEVERE, GAETANO GRECO, AND ALFRED G. RIZZOLO, OF NEWARK, NEW JERSEY.

LOCKING DEVICE.

1,408,854.

Specification of Letters Patent.

Patented Mar. 7, 1922.

Application filed December 20, 1920. Serial No. 431,962.

To all whom it may concern:

Be it known that we, ANDREW BEVERE, GAETANO GRECO, and ALFRED G. RIZZOLO, citizens of the United States, and residents 5 of Newark, county of Essex, and State of New Jersey, have invented certain new and useful Improvements in Locking Devices, of which the following is a specification.

This invention relates to a locking device, and while it is applicable for many 10 different purposes it is particularly designed for holding articles such as milk bottles, these being supported by the neck and can be readily inserted upon delivery, 15 but can not be removed except after the device has been unlocked.

The invention is particularly designed for holding milk bottles and comprises members that swing to closed position so as to 20 support the milk bottle at the top of the neck, the device, when empty, being easily opened by a latch operated from the inside of the device, but when a milk bottle is held in place it prevents access to the latch 25 and it is necessary to operate the latch from a locking means which is normally held against movement by a key-operated lock.

The invention is illustrated in the accompanying drawing, in which Figure 1 is 30 a central vertical section of the device. Figure 2 is a back view thereof, partly broken away to show a part of the interior. Figure 3 is a top view showing the parts open. Figure 4 is a similar view showing the parts 35 closed in locking position. Figure 5 is a view with the locking member removed and several parts shown broken away and in section to more clearly illustrate the operation and the construction of the device, 40 and Figure 6 is a detail perspective view showing the cooperation of the latch and the several parts of the mechanism adjacent thereto.

The device includes two holding members 45 10 and 11, these being preferably arranged in swinging relation, and one of them forms a supporting member and has an extension which provides means for attaching it to a suitable support, such as a window or door 50 casing 12. In the form shown this consists of a perforated back wall 13, through which the screws 14 are inserted, and being screwed on from the inside there is less chance of the device being removed.

55 The holding members 10 and 11 are piv-

oted, as at 15, and are normally swung apart by a spring 16 which is curved around the pivotal pin 15 so that the swinging member 11, when released, assumes the open position shown in Figure 3. The members 60 are provided with an open bottom 17, which is usually provided with a marginal flange 18 so that the bulged upper part 19 of the neck of a bottle 20 acts to suspend the bottle when the holding members are closed, 65 this being clearly seen from Figure 1.

To hold the holding members shut we provide a latch 21 which is hinged at 22 to the plate 23 which extends from the top part of the supporting member 10, the latch 70 being normally held in its closed position by a small spring 24 which abuts at one end on a shoulder 25 on the plate 23, and at the other end on a small stud 26 projecting from the back of the latch. The 75 member 11 has a means for engaging the latch so that the member 11 is held in its closed position, in the form shown this comprising a pin 27 arranged on a plate 28 which projects on the inside of the member 11, so that when the member 11 is swung around to its closed position the spring 24 causes the latch to engage the pin 27 and thus hold the members 80 locked. 85

Projecting downward from the latch is a small finger-piece 29, as will be clearly seen from Figures 2 and 6, which projects downwardly a sufficient distance to provide means for operating the latch, which is readily possible when no element is being held by the device, since the open bottom gives free access in order that the delivery man can unlock the device to insert the bottle in position. After the bottle is in position, of 90 course this bottom being closed, the latch can 95 not be operated from the inside.

To provide for its being secured against unlocking, and also to permit its being unlocked, we arrange the locking member 30 100 which is pivoted, as at 31, to the plate 23 of the supporting member 10 and which has means for providing a key-operated lock thereto, this being preferably by means of the short lever 32 which is in substantial 105 alignment with the perforated projection 33 of the member 10, and the lever 32 being perforated, the staple 34 of the lock 35 can be passed through these perforations to hold 110 this locking member against swinging move-

ment. The hub 36 of the locking member 30 is provided with a tooth 37 which is disposed so that it engages the finger 38 of the latch 21 when the locking member is swung 5 after the lock 35 has been removed therefrom. This permits the release of the bottle from the two holding members.

It will thus be evident from this description that the latch 21 can be operated independently of the locking member, as will be evident from Figure 2, since the finger can be inserted for operating it, but after an article is held in the device this can not be done and the locking member must be released 10 from its locking device, such as a key-operated lock, which insures against removal of the device except by the person having a key therefor.

It will be evident that minor changes may 20 be made in the details of construction without departing from the scope of the invention.

We claim:

1. A locking device comprising a casing 25 consisting of holding members adapted to be fitted together and having an open end that is closed when an element is locked therein, a locking member, a latch for locking the holding members together and operable by the locking member to release the holding members, the latch having means thereon operable from within the casing by means of which the holding members can be released when no element is locked therein.
2. A locking device comprising two members 30 in swinging relation, a latch to secure the members together, a locking means for the latch, the latch being operable from within the casing so that it can be operated independent of the locking means.
3. A locking device comprising two hold-

ing members in swinging relation, one of them having means for attaching it to a support so that it forms a supporting member, a locking member pivoted on said supporting member and adapted to be locked against pivoted movement, and a latch on said supporting member operable by the locking member and also operable independent thereof, the swinging member having 50 means for engagement with the latch, the holding members being open at the bottom so as to receive an article to be held therein, which article when in position prevents access to the latch.

4. A locking device comprising two holding members in swinging relation, one of them having means for attaching it to a support so that it forms a supporting member, a locking member pivoted to the supporting member, both the supporting member and the locking member having arms 60 adapted to be placed approximately in alignment, whereby they can be locked to prevent the locking member from being swung, a latch on the supporting member and adapted to be operated from the inside of the casing independent of the locking member, and disposed so as to be unlatched when the locking member is swung from its locked position, 70 and means on the swinging member for engagement with the latch, the holding members being open at the bottom so as to receive an article to be held therein, which article when in position prevents access to 75 the latch.

In testimony that we claim the foregoing, we have hereunto set our hands, this 17th day of December, 1920.

ANDREW BEVERE,
GAETANO GRECO.
ALFRED G. RIZZOLO.
